UNITED STATES PATENT OFFICE.

GEORGE W. KRAMER, OF PEORIA HEIGHTS, ILLINOIS.

CONCRETE-BLOCK-MAKING MACHINE.

Application filed August 6, 1923. Serial No. 655,835.

This invention relates to machines for making concrete or artificial stone blocks or bricks, more particularly by the "wet" process, the invention having reference generally to automatic power machines of the above-mentioned character, and especially to the molds, the tamping apparatus, and to operating and controlling mechanism relating to such machines.

10 An object of the invention is to provide improvements generally in machines of the above-mentioned character to enable them to be operated expeditiously and with the minimum expense for operators or attendants, and which shall be capable of producing a high grade concrete-block or brick.

Another object is to provide an improved mold in concrete-block-making machines which shall be so constructed as to permit rapid removal of the product from the molds in perfect condition, more particularly when made by the "wet" process.

20 A further object is to provide an improved tamping apparatus and improved operating and controlling mechanism therefor, which shall be so constructed and combined as to insure the highest efficiency in the art of producing compactness of material in concrete-blocks or bricks which shall 30 result in permanently strong and durable blocks or bricks.

A still further object is to provide improved driving means and controlling apparatus for operating the tamping apparatus and other mechanism in machines of the above-mentioned character, to the end that expeditious, efficient and economical operations may result.

With the above-mentioned and other objects in view, the invention consists in a molding machine having a sectional mold provided with a bottom adapted to be heated, means for automatically supplying material to the mold, improved tamping apparatus and means for holding material in the mold compactly during tamping operations, and a power plant mounted in the machine so that its weight shall contribute to the efficiency of the tamping apparatus; and, the invention consists also further in the parts and combinations and arrangements of parts as hereinafter particularly described and farther defined in the claims appended hereto.

55 Referring to the drawings.—Figure 1 is a front elevation of a machine constructed

substantially in accordance with the invention, the tamping and operating mechanism thereof being shown in positions approaching the positions assumed in operation; Fig.

60 Fig. 2 is a fragmentary detail approximately on the line II—II in Fig. 1; Fig. 3 is a rear elevation of the machine, the lower portion of the elevator for supplying the mold being broken away; Fig. 4 is a bottom plan of a novel grip plate comprised in the machine for holding material in the mold and assisting the tamping apparatus to pack the material; Fig. 5 is a sectional elevation of the machine approximately on the line

65 V—V in Fig. 1; Fig. 6 is a fragmentary side view showing upper portions of the machine and mechanism thereon; Fig. 7 is a fragmentary section approximately on the line VII—VII in Fig. 1; Fig. 8 is a sectional elevation approximately on the line

70 VIII—VIII in Fig. 1, the lower portion of the elevator being broken away and the working parts of the machine shown in different positions relatively to those in Figures 1 and 5; Fig. 9 is a fragmentary sectional elevation also on the line VII—VII in Fig. 1 and more particularly on the line

75 IX—IX in the next figure following; Fig. 10 is a fragmentary sectional elevation approximately on the line X—X in Fig. 9; Fig. 11 is a fragmentary horizontal section as on the line XI—XI in Fig. 9; Fig. 12 is a fragmentary section approximately central as on the line VII—VII with various parts of the mechanism in relatively different positions; Fig. 13 is a fragmentary section showing parts in different positions relatively to those in the preceding figure; and, Fig. 14 is a fragmentary section showing parts of the mechanism in different positions relatively to those in the preceding figure.

80 Similar reference characters throughout the various figures of the drawings indicate corresponding elements or features of construction herein referred to in detail.

85 A practical embodiment of the invention includes a stationary main frame in which a carriage is mounted for vertical movement, and a bench arranged below the carriage and constructed as a part of the main frame. The main frame comprises a pair of sills 1 and 1', posts 2 and 3 secured upon one of the sills and posts 4 and 5 secured upon the other sill, the posts being adapted to constitute vertical guides for the car-

riage. A forward top beam 6 is secured upon the posts 2 and 4 and a rear top beam 7 is secured upon the posts 3 and 5, tie bars 8 and 9 being secured to the beams above the posts. The beams are suitably braced relatively to the posts. The frame includes also inclined members 10 and 11 secured to the sills respectively, and also to the rear beam 7 adjacent to the tie bars. Two stands 12 and 13 are mounted upon the top beams and support sheaves 14 and 15 respectively.

The carriage comprises front and rear lower rails 16 and 17 and front and rear upper rails 18 and 19, and a suitable number of transverse members 20 and 21 secured thereto, slide bars 22 and 23 secured to the front and rear rails respectively and guided by the posts 2 and 3 respectively, and similar slide bars 24 and 25 secured to the rails and guided by the opposite posts, the carriage having also tie bars 26 and 26' secured to the lower rails. An equalizer beam 27 is pivoted at its center to the carriage. A stand 28 is secured upon the middle portion of the upper rails of the carriage and supports a sheave 29. The carriage is lifted and controlled partially by means heretofore employed, comprising a shaft 30 mounted in the transverse members of the carriage and having a gear wheel 31 and a winding spool 32 thereon, also a clutch 33 and a governor 34, the clutch having an arm 35 to which a spring suitably supported is connected, and also an oppositely arranged arm 37. A main controlling lever 38 is arranged at the front of the carriage and has a crook 39 extending about the post 2, a short lever arm 40 extending from the crook and being connected to the carriage by means of a bracket 41 provided with a pivot 42 directly supporting the arm 40, a link 43 being connected to the arms 37 and 40 for controlling the clutch. A chain or cable 44 is connected to the winding spool and extends over the sheaves 14 and 15 and under the sheave 29 and is connected to the top of the carriage. A shaft 45 is rotatably mounted in transverse members of the carriage and has a suitable number of cranks 46 to operate the tampers, a gear wheel 47 being secured to the shaft and in engagement with the gear wheel 31. A sprocket wheel 48 is arranged on the crank shaft and provided with a suitable clutch 49 which normally clutches the wheel to the shaft, the clutch being provided with a controlling lever 50 pivoted to the carriage at 51, the lever extending at an inclination above the carriage so as to be carried into contact with the top beam of the main frame when the carriage is elevated and act to un-clutch the sprocket wheel 48 and prevent damage to the carriage. An electric motor 52 is mounted on the lower rails of the carriage and so as to counterbalance the lifting apparatus, and it has a driving sprocket wheel 53 which is connected by a sprocket chain 54 with the sprocket wheel 48. A switch-board 55 is mounted on the carriage so as to be conveniently near to the operator who stands within reach of the controlling lever, and circuit wires 56 are connected with the switch-board and the motor, feed wires 57 being connected to the switch-board, and a suitable switch 58 is mounted on the switch-board. The winding spool 75 being adjacent to one end of the carriage, the motor is arranged adjacent to the opposite end of the carriage, the machinery being so disposed as to cause the carriage to be practically balanced on the sheave 29, all affording considerable weight to force down the necessary tampers.

In order to drive machinery on the bench of the main frame a transmission shaft 59 is rotatably mounted on the inclined members 10 and 11 of the main frame in suitable journal boxes 60 and 61 supported by the members, and the shaft has sprocket wheels 62 and 63 secured thereto. The shaft extends out beyond the frame and has a sprocket wheel 64 secured thereto whereby to drive the shaft. A stub axle 65 is supported on the upper rearward portion of the main frame and supports a guide sheave 66, another stub axle 67 being secured to the front post 4 and supports a guide sheave 68 at a suitable distance lower than the shaft 59. A stub axle 69 is secured to the upper portion of the carriage so as to be vertically above the axle 67 and it supports a guide sheave 70. The shaft 45 extends out beyond the frame and has a sprocket wheel 71 secured thereto, to which a sprocket chain 72 is connected that extends about the sheave 66 and partially about the sprocket wheel 64 and also under the sheave 68 and over the sheave 70, this permitting the shaft 45 to drive the shaft 59 during movement of the carriage without slackening or tightening the driving chain.

The bench is provided with a base plate 73 that is arranged between the sills 1 and 1' and a compact substantial bench frame comprising side members 74 and 74' and transverse members 75 is secured upon the plate, standards 76 and 77 being secured on the plate adjacent to one side of the bench frame and other standards 78 and 79 secured upon the plate adjacent to the opposite side of the bench frame. The standards extend upward higher than the bench frame and support a hopper 80 which is arranged rearward of the plane of movement of the carriage. Inclined frame members 81 and 82 are secured to the hopper and to the rearward top beam 7 and may suitably assist in supporting the shaft 59. The hopper has a shiftable bottom, which will be further described, and it extends upward to a suitable height to afford ample capacity to receive material from an

elevator which comprises side bars 83 and 84 connected to the top beam 7 and extending downward and rearwardly at an inclination, a bottom 85 of suitable length being connected to the side bars. A shaft 86 is mounted on the side bars and has a sprocket wheel 87 secured thereto that is opposite to the sprocket wheel 63. A guide wheel 88 is mounted on a stub shaft 89 that is supported on one of the side bars of the elevator. Sprocket wheels 90 are secured to the shaft 86 and drive elevator chains 91 that are guided on wheels 92 mounted on the shaft 93 supported on the lower portions of the side bars, the chains being provided with blades 94 that are drawn upward on the bottom of the elevator to elevate the material and force it from the upper end of the bottom 85 above the hopper. The elevator preferably is steadied by braces 95 and 95' connected thereto and to the standards that support the hopper. The wheel 87 is automatically driven as will be hereinafter explained.

The mold for concrete-blocks comprises a box which has a stationary back wall 96 from the top of which a table 97 extends rearward, the wall being fixed on the mold bench, the bench supporting front members 98 and 98' opposite to the back, and the mold has end members 99 and 99' hinged to the bench, as hitherto. The mold box comprises a front member 100, and a relatively right angle bottom member 101. The bench frame supports a shaft 102 having rollers 103 thereon against the outer side of the front member 100, and the front member preferably has a shield 104 thereon to protect the rollers from concrete that may be worked over the top edge of the mold. A cross-head 105 is guided for vertical movement between members of the bench and it has connecting rods 106 and 106' connected thereto and pivoted to the bottom member 101 whereby to elevate the mold box and tilt it over the rollers 103. Chains 107 are connected to the cross-head and to a winding-shaft 108 mounted in the bench frame and having a sprocket wheel 109 loose thereon, which may be connected to the shaft by means of a suitable clutch 110, operated by means of a connecting rod 111 that is connected therewith and also with a foot lever 112 pivoted to the bench frame and provided with a retracting spring 113 that is so connected with the clutch as to normally unclutch the sprocket wheel. The shaft 108 being in the front portions of the bench, a guide wheel 114 is supported on the rearward portion of the bench opposite to the wheel 109, and a guide wheel 115 is supported intermediate of the forward and rearward portions of the bench and higher than the wheel 109. A sprocket chain 116 is arranged in connection with the wheel 63 and the wheel 87, extending over the wheel 88, under the wheels 114 and 115 and about the wheel 109, whereby the elevator is operated and also the shaft 108 is rotated when desired. The bottom member 101 of the mold box supports a mold bottom 117 that has a chamber 118 therein to receive steam whereby to heat the mold bottom, and the face plate which in some cases may be placed upon the bottom to mold rock-face blocks. A suitable steam-boiler 119 is arranged in a convenient place, and a flexible conduit is connected to the top thereof and extends into the steam chamber 118 and nearly to the top thereof remote from the front member 100 to conduct steam into the chamber, a flexible conduit 121 being connected to the bottom of the steam-chamber adjacent to the front member 100 and with the steam-boiler to conduct the water of condensation back to the steam-boiler. A suitable pallet 122 for each block is arranged against the front member 100 of the mold box and rests on the bottom 117.

The lower end of the hopper 80 terminates at a suitable distance above the table 97, and a drawer is provided for moving the concrete from the hopper to the mold, the material being received onto the table from the hopper, the drawer comprising a main part having sides 123 and 124, a transverse wall 125, a plate 126 extending rearward from the top of the wall in contact with the lower end of the hopper to constitute a temporary hopper bottom, and a front wall 127 connected to the sides of the drawer and extending downward a short distance. A strike-off roll 128 is mounted under the front wall 127 in connection with the sides of the drawer. The sides of the drawer have each a flange 129 guided between rollers 130 and 131 mounted on the standards to support the hopper to relieve the drawer from wear upon the table 97. The strike-off roll 128 has a sprocket wheel 132 on its supporting shaft and preferably also a suitable clutch 133 which obviously may be variously operated as may be desired. The strike-off roll is automatically rotated in one direction and to this end a guide sheave 134 is supported on one of the standards adjacent to the front portion of the hopper, and a similar sheave 135 is supported adjacent to the rearward portion of the hopper; a guide sheave 136 is supported on the drawer adjacent to its rearward end, and a sprocket chain 137 extends about the sprocket wheels 62 and 132 and extends also under the guide wheels 134 and 135, whereby the strike-off roll is rotated while the drawer is permitted to be moved forward or backward.

The tamping apparatus comprises two frame bars 138 and 138' suitably guided in

the carriage for vertical movement relatively to the carriage, and a head bar 139 is secured to the frame bars so as to be above one of the top rails of the carriage to be engaged thereby and carried upward with the carriage. A guide frame or bar 140 is arranged in proximity to the lower ends of the frame bars and the bars extend through and are secured to the guide frame. 5 A novel grip plate 141 is secured to the lower ends of the frame bars 138 and 138', the grip plate being arranged above the mold and so as to press down upon the material in the mold during tamping operations. The grip plate, corresponding to the mold, is oblong in plan and the under side thereof has a guard projection 142 adjacent to each end thereof which assist the tampers to force the material downward 10 in the mold and also prevent the material from working over the tops of the ends of the mold. The under side of the grip plate has also a suitable number of cavities 143 from each of which an aperture 144 extends. The under side of the grip plate has also a suitable number of wedges or V-shaped spreaders 145 thereon arranged intermediately of the cavities. A suitable number of tamper bars 146 are connected to the cranks 46 and extend loosely through the guide frame 140 and also through the apertures 144, the lower end of each tamper bar having a tamping-head 147 thereon that may be received in the adjacent cavity 143. 15 The spreaders operate to force the concrete material to the tamping-heads to insure compactness of the material, while the grip plate is forced down by its own weight and that of the guide bar and the frame bars. 20 In order to augment the weight on the grip plate during the final tamping operations the frame bars 138 and 138' have notches 148 in the forward side thereof, and a latch bar 149 is pivoted to the transverse bar 26 and extends across the other bar 27 and downward to the lower rail 16 of the carriage, permitting it to be swung back into the notches so as to cause the 25 weight of the carriage and machinery thereon to be exerted downward on the grip plate at times when the mold contains the maximum quantity of material and a surplus of material piled higher than the mold. 30 For the purpose of operating and controlling the drawer to supply the mold with material, the upper forward portion of the drawer is provided with a pivot bar 150 to which two operating bars 151 and 152 are connected and arranged to extend rearwardly, each operating bar having a notch 153 adjacent to its end and another notch 154 at a suitable distance from the end, the notches being in the under side of the bar. 35 A shaft 155 is mounted on the rearward standards that support the hopper, being 40 rotatable, and two bell cranks 156 and 157 are secured to the shaft. One arm of each bell-crank has a wrist-pin 158 thereon to be carried into the notch 154 of the adjacent operating bar, the bars being at 45 times lowered until the notches 153 receive the portions of the shaft 155 adjacent to the bell-cranks. Two connecting rods 159 and 160 are pivoted to the opposite arms of the bell-cranks respectively, and also to the 50 carriage, preferably to the equalizer beam 27 pivoted to a vertical frame bar secured to the lower rearward rail 17 thereof, whereby the bell-cranks are operated synchronously with the movements of the carriage. 55 Preferably, a coil spring 161 is connected to each operating bar and connected to a convenient part of the mold bench or stationary frame. 60 When it is desired to make hollow concrete-blocks, which usually are preferable, the back wall 96 of the mold is provided with a suitable number of apertures 162 in which cores 163 are horizontally arranged, half cores 164 being arranged adjacent to 65 the ends 99 and 99' of the mold. The rear end of each core has a guide bar 165 fixed thereon that extends rearward and is movably guided in a bearing 166 supported by the bench frame. A yoke 167 is fixed to the rear end of one of the cores and may be carried to and stopped against a bearing post 168 supported by the bench frame which may be adapted to assist in guiding the bars 165. A controlling bar 169 is pivoted to the yoke and extends over and beyond the guide post, so as to be supported thereby and it has a cross bar 170 secured thereto, to which coil springs 171 and 171' are connected that are connected to a suitable part of the bench, preferably adjacent to the under side of the table 97, being designed to thrust the cores forward 70 into the mold in advance of the charging of the mold with concrete material. The controlling bar 169 has an upwardly extending neck 172 fixed thereon from which an arm 173 extends rearward between the sides 123 and 124 of the drawer, the under side of the arm having a latch projection 174 thereon and also an upwardly extending curved guide 175, the projection being arranged to engage the outer side of a cross bar 176 fixed to the sides of the drawer and across which the arm may be projected. The neck 172 has also an abutment 177 thereon projecting forwardly to be engaged by a cam 178 that is secured to the shaft 155 whereby to forcibly start retraction of the cores from a molded block when the bell-cranks are powerfully operated. In order to release the latch projection to permit sudden projection of the cores a cam 179 is secured to a shaft 180 mounted on the rearward portion of the bench frame, the cam being 75 80 85 90 95 100 105 110 115 120 125 130

beneath the controlling bar 169 and operating to swing the bar upward so as to release the latch projection, the shaft being provided with a crank arm 181 to which a rod 182 is connected which in turn is connected to a foot lever 183 pivoted on the lower portion of the bench frame and provided with a spring 184 connected to a part of the frame to retract the lever and the cam. Thus equipped with cores a hollow block 185 may be molded in the machine.

In practical use, having started the motor, a "wet" concrete mixture is supplied in any desired manner to the elevator on which the mixture is drawn upward by the flights 94 and discharged into the hopper 80. The mold being set to receive the material and the mold bottom heated as intended, the drawer is in retracted position which permits the concrete to fall upon the table 97 which then constitutes the bottom of the hopper. At the beginning the carriage is in elevated position and the clutch 49 enables the motor to drive the machine, the bell-cranks 156 and 157 being so tilted that a wrist-pin thereon shall be in the notches 154 in the operating bars, the drawer being retracted, therefore receiving a charge of material. The drawer holds the cores in retracted position, as seen clearly in Fig. 12. The operator manipulates the main control lever 38 as is customary to permit descent and control of the carriage which lowers the tamper bars and the grip plate to co-operate therewith in the tamping operations. As the carriage descends it causes tilting of the bell-cranks which acting on the operating bars cause projection of the drawer; and as the drawer begins to advance the operator depresses the foot lever 183 which pulls down the rod 182 and operates the cam 179 so as to disengage the latch projection 174 from the drawer, the springs 171 then suddenly thrusting the cores into the mold before the mold is charged with material by the advancing drawer. As the drawer advances the plate 126 temporarily becomes the bottom of the hopper and prevents further flow of the material, the strike-off roll 128 preceding the movement of the concrete material. Following the charging of the mold with material the carriage is permitted to lower the tamper bars into the material in the mold, the weight of the carriage and the equipment thereon forcing the tamper bars downward, the grip plate being free to operate by the force of gravity to hold down the material while the tamping heads pack the material in the mold with rapid short strokes, the tamper bars descending one at a time in succession. While the material is being tamped so as to be packed under and between the cores, the material is held down by the grip plate and the V-shaped spreaders 145 cause the material above the cores

to be forced over to the tamper bars. The "wet" mixture having been thoroughly packed until the mold is nearly filled, additional mixture is fed to the mold so that there shall be a surplus of material which holds up the grip plate sufficiently high to bring the spreaders above the plane of the top of the mold during the final tamping, during which the weight of the carriage and its equipment is transferred by means of the latch bar 149 onto the grip plate, thus insuring compactness of the upper portion of the concrete block, resulting in the "water proofing" of the block throughout. The tamping operations having been completed, the carriage is caused to be elevated, the upward movement of the carriage carrying up the tamper bars and causing the latch 149 to be automatically released from the notches 148, permitting the carriage to engage the head bar 139 whereby the grip plate frame is elevated with the carriage. As the carriage rises the bell-cranks are automatically tilted to retract the drawer and the cores. As the drawer is retracted the strike-off roll 128 is drawn across the top of the mold and the molded block and is rotated automatically by its train of gearing, the roll and the front wall of the drawer forcing the surplus material back onto the table 97, the roll in its travel being turned in the direction contrary to the rolling movement and causing troweling of the surface of the block. As the bell-cranks are tilted the shaft 155 is rotated and the cam 178 is swung around into engagement with the abutment 177 whereby the cores are powerfully started to move backward before the latch projection 174 is engaged by the drawer, the engagement subsequently occurring to enable the drawer to complete the withdrawal of the cores and hold them in retracted position, the different steps in the movement being illustrated by broken lines in Fig. 13. The molding of the block having been completed the operator depresses the foot lever 112 whereby to operate the clutch 110 to connect the wheel 109 to the winding-shaft 108, whereby the bottom 101 of the mold box is directly forced upward until the front 100 of the mold box is tilted over the rolls 103, the movement of the mold box causing clean stripping of the concrete-block from the back and ends of the mold and being brought to a convenient position for removing the block on its pallet from the mold box. The heated mold bottom partially dries the material in contact therewith and prevents sticking of the material to the bottom as the block is drawn away from the bottom, thus insuring a perfect face on the block which is to become a portion of a wall face. During the movement of the carriage the bell-cranks are or may be moved more than necessary to cause

movement of the material drawer, and as the bell-crank lower the controlling bars the shaft 155 is received in the notches 153 so as to prevent further unnecessary downward movement of the bars and permitting the wrist-pin 158 to be carried down from the notches 154, the wrist-pin being again brought up into the latter notches as the carriage moves upward and the drawer is required to be retracted by means of the bell-crank.

What I claim as new is:—

1. A machine including a mold having an artificially heated bottom, a hopper, a movable drawer to transfer material from the hopper to the mold, and tamping apparatus to operate on the material and pack it on the heated bottom thereof.
2. A machine including a mold, a movable drawer to fill the mold, a carriage and connections to automatically move the drawer synchronously therewith, tamping apparatus supported by the carriage, and a strike-off device carried by the drawer.
3. A machine including a mold, means for heating the mold, tamping apparatus to operate in the mold, a hopper, a drawer to transfer material from the hopper to the mold, and connections co-operating with the tamping apparatus and the drawer to move the drawer in synchronism with the operations of the tamping apparatus.
4. A machine including a mold, means to conduct heating medium to the mold, driving mechanism, tamping apparatus operated by the driving mechanism, a carriage for the tamping apparatus, a drawer to fill the mold controlled by the carriage, a rotary strike-off roll mounted on the drawer, and a train of gearing connected with the driving mechanism and the strike-off roll to rotate the roll.
5. A machine including a mold, a carriage vertically movable above the mold, a grip plate to exert gravity pressure on plastic material in the mold and provided with a frame to be periodically lifted by the carriage, and tamper bars actuated on the carriage and extending movably through the grip plate to operate on the plastic material in the mold.
6. A machine including a mold box having a vertically movable and tilting member, a winding-shaft and connections to lift and tilt the mold box member, tampers to co-operate with the mold box, operating gearing for the tampers, a train of gearing connected with the operating gearing and also loosely with the winding-shaft, and means for clutching the winding-shaft at will to the train of gearing.

7. A machine including a vertically movable and tiltable mold box, tampers to operate in the mold box, a vertically movable carriage having guides for the tampers,

power driving mechanism for operating the tampers mounted on the carriage, and means for having connection with the driving mechanism and the mold box for lifting and tilting the mold box.

70

8. A machine including a mold, a hopper, a drawer to move material from the hopper to the mold, a vertically movable carriage provided with tamper guides, tampers guided by the guides to operate in the mold, driving mechanism mounted on the carriage to operate the tampers, and means having equalized connection with the carriage and the drawer for operating the drawer.

75

9. A machine including a frame, a mold box vertically movable and tiltable on the frame, tampers to operate in the mold box, a winding-shaft and connections to lift and tilt the mold box, a vertically movable carriage having means to guide the tampers, a train of gearing to operate the tampers including a driven wheel loose on the winding-shaft, and means to clutch the driven wheel to the winding-shaft.

80

10. A machine including a mold, a carriage vertically movable above the mold, a grip plate to exert gravity pressure on plastic material in the mold and having a frame fixed thereto to be periodically lifted by the carriage, tamper bars actuated on the carriage and guided in the grip plate to operate in the mold to pack the plastic material under the grip plate, and means for imparting the weight of the carriage to the frame of the grip plate.

85

11. A machine including a mold for plastic material comprising a mold back, a roll supported opposite to the mold back, a mold box comprising a front member and a relatively right-angled bottom member, mold sides, a mold bottom supported upon said bottom member and having a heating-chamber therein, tampers to operate in the mold, and means to raise the mold box and tilt the front member thereof over said roll.

90

12. A machine including a mold, cores movable into or out of the mold, a hopper, a drawer operating to move material from the hopper to the mold, means to connect the cores with the drawer to move the cores by the drawer out of the mold, means to start the cores in advance of confection thereof with the drawer, means to release the cores from the drawer when out of the mold, and means to thrust the cores into the mold suddenly when released and in advance of operation of the drawer.

95

13. A machine including a stationary frame, a carriage vertically movable in the frame, a mold below the carriage, tamper bars movably guided by the carriage to operate in the mold, driving means to operate the tamper bars, a motor mounted on the carriage and connected with the driving means, means actuated by the driving means

100

105

110

115

120

125

130

135

140

for raising the carriage, and means actuated by the descent of the carriage and the motor thereon to retard the downward movement of the carriage.

- 5 14. A machine including a stationary frame, a carriage vertically movable in the main frame, a mold below the carriage, tamper bars guided by the carriage, driving mechanism for the tamper bars mounted 10 on the carriage, an elevator fixed to the stationary frame, a rotatable shaft mounted on the stationary frame, elevator gearing having connection with the rotatable shaft to be operated thereby, and means constantly 15 connected with the driving mechanism and the rotatable shaft to rotate the shaft.
15. A machine including a mold, a hopper, an elevator, a drawer under the hopper, a vertically movable carriage, a rotary 20 strike-off roll mounted on the drawer, operating means for the drawer connected therewith and with the carriage, tampers guided 25 the carriage to operate in the mold, driving mechanism on the carriage to operate the tampers, a train of gearing connected with the driving mechanism and the strike-off roll, and driving means for the elevator connected with the train of gearing.

- 30 16. A machine including a frame, a mold on the frame, a hopper, a drawer to move material from the hopper to the mold, a carriage vertically movable in the frame and provided with tamper guides, means including an equalizer and connected with the drawer and the carriage to operate the drawer on movement of the carriage, tampers guided by the tamper guides, a rotary strike-off roll carried by the drawer and having a driving wheel thereon, and a train 35 of gearing to operate the tampers having operative connection with the driving wheel of the strike-off roll.

- 40 17. A machine including a stationary frame, a vertically movable and tilttable mold box, tampers to operate in the mold box, a winding-shaft and connections to lift and tilt the mold-box, a driven wheel loose on the winding-shaft, a clutch to connect the driven wheel operatively to the winding-shaft, a driving wheel mounted on the stationary frame, a carriage movable in the stationary frame, a belt connected with the driving wheel and the driven wheel, and power operating mechanism for the tampers 45 mounted on the carriage and having driving connections to rotate the driving wheel.

- 50 18. A machine including a mold, a vertically movable carriage, a grip plate having a frame guided by the carriage for vertical movement, the under side of the grip plate having wedge-shaped spreaders thereon, a guide bar secured to the grip plate frame above the plate, a crank-shaft rotatably mounted on the carriage, tamper bars connected to the crank-shaft and extending mov-

ably through the guide bar and also through the grip plate between the spreaders, the tamper bars being weighted by the carriage when in operation, and means to periodically weight the grip plate by the carriage.

- 70 19. A machine including a stationary frame, a carriage vertically movable in the main frame, a stationary bench below the carriage, a mold on the bench, a hopper on the bench higher than the mold, a power generator mounted on the carriage, a crank-shaft mounted on the carriage and driven by the generator, tamper bars guided by the carriage and operated by the crank-shaft, a grip plate to co-operate with the tamper bars, means for moving and controlling the carriage having connection with the crank-shaft, a rotatable shaft mounted on the stationary frame and having connection with the crank-shaft to be rotated thereby, an elevator operated by the rotatable shaft, a drawer operated by the carriage, and a rotary strike-off roll on the drawer operated by the rotatable shaft.

- 75 20. In a molding-machine, the combination with an open-top mold, of tampers and a grip plate co-operating to pack material in the mold, the tampers working in the material and the grip plate exerting gravity force and bearing down upon the material.

- 80 21. In a molding machine, the combination with a mold, cores projectable into the mold, and a drawer to move material to the mold, of operating means connected to the mold and connectible to the drawer to withdraw the cores from the mold, and a spring connected to said means and supported to rapidly project the cores into the mold.

- 85 22. In a molding-machine, the combination with a mold, a vertically movable carriage, and a horizontally movable drawer, of a bell-crank pivotally supported adjacent to the drawer, a connecting rod pivoted to the carriage and to the bell-crank, and an operating bar pivoted to the drawer and to the bell-crank.

- 90 23. In a molding-machine, the combination with a stationary frame, a carriage vertically movable in the frame, and an open-top mold below the carriage, of a crank-shaft rotatably supported on the carriage, tamper bars connected to the crank-shaft, means controlled by the carriage to guide the tamper bars to operate in the mold, and a power generator bodily supported on the carriage and rotating the crank-shaft at high speed.

- 95 24. In a molding-machine, the combination with an open-top mold, of a grip plate to press down upon material in the mold and having wedges to spread the material, a frame secured to the grip plate and bearing down thereon, tamping-heads to operate under the grip plate to pack the material and having tamper bars extending through the grip plate, a guide for the tamper bars se-

cured to and bearing down on the frame, and means to operate the tamper bars.

25. In a molding-machine, the combination with a mold back, mold ends, and a vertically movable and tilttable mold box to support a pallet, of a mold bottom supported by the mold box and having a steam-chamber therein, a steam-boiler, a flexible conduit connected with the upper portion of the steam-boiler and extending into the steam-chamber, a flexible conduit connected with the bottom of the steam-chamber and with the steam boiler below the top thereof, and tamping apparatus to operate above the mold bottom.

26. In a molding-machine, the combination with an open-top mold, of a grip plate to press down upon material in the mold and having cavities in the under side thereof, tamper bars extending movably through the cavities and having tamping-heads thereon to operate below the grip plate and also upward into the cavities respectively, a carriage vertically movable above the grip plate, a frame secured to the grip plate and vertically movable in the carriage, and means mounted on the carriage to operate the tamper bars.

27. In a molding-machine, the combination with a mold, cores projectable into the mold, and a drawer to move material to the mold, of an operating bar connected to the cores, means to latch the bar to the drawer for retracting the cores, means to engage and forcibly move the operating bar in advance of action by the drawer to retract the cores, means to unlatch the operating bar from the drawer, and means for suddenly moving the operating bar when unlatched to project the cores in advance of movement of the drawer to move the material.

28. In a molding-machine, the combination with an open-top mold, a hopper, a drawer to move material from the hopper to the mold, and a rotary strike-off roll carried by one end of the drawer and provided with a sprocket wheel to rotate it, of transmission shaft supported higher than the hopper a sprocket wheel secured to the transmission shaft, a guide sheave carried on the opposite end of the drawer, two guide sheaves supported in fixed positions adjacent to the drawer, and a sprocket chain extending about the two sprocket wheels and all the guide sheaves.

29. In a molding-machine, the combination with an open-top mold, and a carriage vertically movable above the mold, of a pair of frame bars vertically movable in the carriage and having each a notch in one side thereof, a latch bar pivoted to the carriage to be moved into said notches to prevent upward movement of the frame bars in the carriage, a grip plate secured to the lower

ends of the frame bars, tamper bars movably guided in the grip plate and having tamping-heads below the plate, and means on the carriage to operate the tamper bars.

30. In a molding-machine, the combination with an open-top mold, and a carriage vertically movable above the mold, of a frame vertically movable in the carriage, a grip plate secured to the frame, a guide bar secured to the frame above the grip plate, tamper bars extending movably through the guide bar and the grip plate to work in the mold, means on the carriage to operate the tamper bars, means to impart weight of the carriage to the frame, means to raise the carriage, and means to automatically retard descent of the carriage.

31. In a molding-machine, the combination with an open-top mold, and a carriage vertically movable above the mold, of a pair of frame bars vertically movable in the carriage, a head bar secured to the frame bars to be engaged and lifted by the carriage, a grip plate secured to the lower ends of the frame bars and having apertures therein, the under side of the grip plates being provided with wedge-shaped spreaders and also projections adjacent to the ends of the plate, tamper bars vertically guided in said apertures, and means mounted on the carriage to operate the tamper bars.

32. In a molding-machine, the combination of a stationary frame, a mold, means to heat the mold, a carriage vertically movable in the frame above the mold, a winding-spool mounted in the carriage adjacent to one side thereof, a power generator mounted as a counterbalance in the carriage adjacent to the opposite side thereof, a crank-shaft mounted in the carriage and rotated by the power generator, means enabling the crank-shaft to operate the winding-spool, means to enable the winding-spool to centrally lift the carriage, tamper bars connected to the crank-shaft, and a guide for the tamper bars controlled by the carriage.

33. In a molding-machine, the combination with a vertically movable mold box, a movable crosshead and connections to lift the mold box, a winding-shaft, and a cable connected to the winding-shaft and the cross-head, of a driven sprocket wheel loose on the winding-shaft, a transmission shaft supported higher than the winding-shaft, a driving sprocket wheel secured to the transmission-shaft, two guide wheels supported in the region of the winding-shaft, a sprocket chain extending about the two sprocket wheels and the two guide wheels, and means to clutch the driven wheel at will to the winding-shaft.

34. In a molding-machine, the combination with a vertically movable mold box, a winding-shaft and connections to lift the mold box, and a hopper, of an elevator to

supply the hopper, an elevator-driving sprocket wheel, a driven sprocket wheel loose on the winding-shaft, means to clutch the driven sprocket wheel to the winding-shaft, a transmission shaft supported higher than the elevator-driving wheel, a sprocket wheel secured to the transmission shaft, two guide wheels supported in the region of the winding-shaft, a guide wheel supported on the elevator, and a sprocket chain extending about all the sprocket wheels and the guide wheels.

35. In a molding-machine, the combination with a stationary frame, a carriage vertically movable in the frame, a mold, and tampers guided by the carriage, of a crank-shaft rotatably mounted on the carriage and connected to the tampers, a sprocket wheel secured to the crank-shaft, a rotatable transmission shaft mounted on the stationary frame, a sprocket wheel secured to the transmission shaft, two guide sheaves mounted on the stationary frame, one sheave higher and

the other far lower than the transmission shaft, a guide sheave mounted on the carriage higher than the crank-shaft, and a sprocket-chain extending about the two sprocket wheels and all the guide sheaves.

36. In a molding-machine, the combination with a mold, and a drawer horizontally movable above the mold, of a carriage vertically movable above the drawer, an equalizer pivotally connected at its middle portion to a median portion of the carriage, two bell-cranks pivotally supported adjacent to the opposite sides respectively of the drawer, two connecting rods pivoted to the opposite ends respectively of the equalizer and also to the bell-cranks respectively, and two operating bars pivoted to the drawer and having operative connections with the bell-cranks respectively.

In testimony whereof, I affix my signature on the 30th day of June, 1923.

GEORGE W. KRAMER.
